UNITED STATES PATENT OFFICE

92,698

DESIGN FOR A PASTEURIZER

Arthur H. Boileau, Cedar Rapids, Iowa, assignor
to Cherry-Burrell Corporation, Chicago, Ill.,
a corporation of Delaware

Application May 7, 1934, Serial No. 51,712

Term of patent 7 years

To all whom it may concern:

Be it known that I, ARTHUR H. BOILEAU, a citizen of the United States, residing at Cedar Rapids, in the county of Linn and State of Iowa, have invented a new, original, and ornamental Design for a Pasteurizer, of which the following is a specification, reference being had to the accompanying drawing, forming a part thereof in which—

Fig. 1 is a front perspective view of the article, showing my new design.

Fig. 2 is a rear perspective view; and

Fig. 3 is a top plan view.

I claim:

The ornamental design for a pasteurizer as shown.

ARTHUR H. BOILEAU.
